UNITED STATES PATENT OFFICE.

JOHN H. GOEHST, OF CHICAGO, ILLINOIS, ASSIGNOR TO FEDERAL ELECTRIC COMPANY, OF CHICAGO, ILLINOIS, A CORPORATION OF ILLINOIS.

PORTABLE ELECTRIC LAMP.

No. 806,409.

Specification of Letters Patent.

Patented Dec. 5, 1905.

Application filed February 16, 1905. Serial No. 245,919.

To all whom it may concern:

Be it known that I, JOHN H. GOEHST, a citizen of the United States, residing at Chicago, in the county of Cook and State of Illinois, have invented certain new and useful Improvements in Portable Electric Lamps; and I do hereby declare that the following is a full, clear, and exact description thereof, reference being had to the accompanying drawings, and to the letters of reference marked thereon, which form a part of this specification.

This invention relates to a novel portable electric lamp designed to be carried from place to place within a limited range permitted by a practicable length of cord. The lamp is useful in a bedroom or sick-room and may practically be used in connection with a cord of a length permitting the lamp to be placed upon a dresser, table, or the like, to be attached to or hung upon the frame of a bed or couch, or to be affixed to a wall or other vertical support in the manner of a bracket.

The invention consists in the matters hereinafter set forth, and more particularly pointed out in the appended claims.

In the drawings, Figure 1 is a perspective view of a lamp made in accordance with my invention, showing the same supported on a table. Fig. 2 illustrates the manner of supporting the same on the frame of a bed or couch. Fig. 3 illustrates the manner of supporting the device on a vertical wall to constitute a bracket. Fig. 4 is a detail showing the swivel connection of the lamp-socket with the lamp-body.

A lamp embodying my invention embraces, in general terms, a lamp body or stand A of any desired contour provided with a wide base A' and with a handle A². Said handle is shown as hinged at its upper end to a lug a near the upper end of the body and is free at its lower end from the lamp-body.

B designates a lamp-socket, B' a lamp therein, and B² a shade and reflector attached to the socket in a manner to direct the light in a desired direction. Said lamp-socket is affixed to a stem or post B³, which has swivel connection with the lamp-body, whereby the lamp may be swung at varying angles to body and locked in such adjusted position. The swivel connection between said stem B³ and the lamp-body is made as follows:

Said lamp-body is provided at its upper end with a laterally-curved arm a', which is provided at its outer end with an offset portion a², as shown in Fig. 4. The stem or post B³ of the socket B is also provided with an offset portion b, attached in overlapping relation to the offset end of the arm a'. Said overlapping parts a² and b of the arm and stem are made rounded or of disk form and are connected together by means of a clamping-screw b', extending through registering openings in said parts and having screw-threaded engagement with one of said parts. When said screw is released, the socket may be adjusted at the angle desired and the screw serves to lock the parts in their adjusted positions.

As herein shown, the circuit-wires C enter the hollow upper end of the lamp-body through an insulating-bushing a³ at the top of the body, and the arm a', by which the lamp-socket is supported on the body, is made hollow so as to permit said circuit-wires C to pass therethrough to the lamp-socket. By reason of the offset connection of the arm and stem a' B³ the wires pass directly from the hollow arm a' to the stem or post B³ without interference with the swivel connection between said parts.

E designates a switch-plug which is connected by cords e with the proper cut-off terminals, said cords entering the hollow lamp-body through an insulating-bushing a⁴ near the base of the lamp-body.

In Fig. 1 is indicated the manner of using said lamp as an ordinary table-lamp. When so used, the angle of the lamp-socket and lamp may be varied, as indicated in full and dotted lines in said figure to direct the light either downwardly or laterally.

In Fig. 2 the lamp is shown as suspended on the head-frame F of a bed or couch, and when so supported it may be conveniently used as a reading-lamp by a person reclining on said bed or couch. The pivoting of the handle to the lamp-body facilitates such use of the lamp.

In Fig. 3 I have shown the lamp when used in the manner of an ordinary wall-bracket. For this purpose the base of the lamp is provided with a small hole a⁵, through which a nail G or the like may be driven, and thereby connect the lamp with a vertical wall or other like support.

The lamp herein shown is an exceedingly convenient and practical device and admirably lends itself to many and varied uses, a few of which have been herein suggested. The lamp 5 is attractive in its appearance and occupies but little space.

I claim as my invention—

1. A portable electric lamp comprising a lamp-body provided with a supporting-base, 10 a lamp-socket, a hinged connection between said socket and the upper part of the lamp-body, and a hooked-shape handle attached at one end to the upper end of said lamp-body and constructed to constitute means by which 15 the lamp may be suspended.

2. A portable electric lamp comprising a lamp-body, a lamp-socket, a hinged connection between said socket and the upper part 20 of the lamp-body, and a handle for said body pivoted at one end to the upper end of said

lamp-body and free from said body at its other end.

3. A portable electric lamp comprising a lamp-body provided with a base having therein an opening adapted to receive a suspending-pin, a lamp-socket, a hinged connection between the upper part of the lamp-body and socket constructed to lock the socket in different angular positions relatively to the body, and a handle for said body attached at one end 25 to the upper end of the lamp-body, and free from said body at its other end.

In testimony that I claim the foregoing as my invention I affix my signature, in presence of two witnesses, this 7th day of February, A. 35 D. 1905.

JOHN H. GOEHST.
